UNITED STATES PATENT OFFICE.

FRANK C. APPLEGATE, OF PHILADELPHIA, PENNSYLVANIA.

BOTTLE-CAPPING MACHINE.

1,316,996.

Specification of Letters Patent. Patented Sept. 23, 1919.

Application filed August 8, 1916. Serial No. 113,726.

To all whom it may concern:

Be it known that I, FRANK C. APPLEGATE, a citizen of the United States, and a resident of Philadelphia, in the county of Philadelphia and State of Pennsylvania, have invented certain new and useful Improvements in Bottle-Capping Machines, of which the following is a specification.

My invention relates to machines adapted to seal the mouths of bottles by means of caps having corrugated rims. One of the objects of my invention is to provide a machine of this character with an improved means for holding a bottle sealing cap; another object is to provide an improved capping die adapted to force the rim of the cap over the lip of the bottle; a further object is to provide improved means for forcing the bottle with the cap outwardly of the die.

With the above and related objects in view, my invention comprises the construction, combination and arrangement of parts, a practical embodiment whereof is illustrated in the accompanying drawing and embraced within the scope of the appended claims.

In the said drawing:—

Figure 1 is a side elevation of my machine; Fig. 2 is a fragmentary vertical section thereof; Fig. 3 is an inverted plan of my improved mounting die and ejecting device, and Fig. 4 is a view of a cap adapted to be mounted by means of my improved machine.

Referring more particularly to the drawing for a detail description of my invention:—

1 represents a pedestal, 2 represents its base which is slotted for clamping onto a table or bench, 3, 4 represents a winged bolt adapted to clamp the base to said bench, 5 represents a bracket provided with a vertical guide 6, and with a horizontal bearing 7. 8 represents a vertical rack movably supported by the guide 6, 9 represents a platform mounted on top of the rack, 10 represents a shaft supported by the bearing 7, 11 represents a gear mounted on the shaft in mesh with the rack 8, and 12 represents a lever for operating the gear. The pedestal is provided with a head 13, centrally above the platform 9. 14 represents a cap holder provided with a horizontal opening for inserting a cap. The holder 14 is provided with a sleeve 15 extended upwardly thereof and of a diameter larger than that of the

holder and approximately equal to that of the flange 13' of the head, whereby the holder is suspended from the head. The holder is provided with a contracted rim 16, 60 adapted to support the rim of a cap. The rim 16 is then expanded into a conical hood 17. The mounting die comprises a hollow cylinder 18 adapted to be projected through the bore of the head and is provided with 65 perforated top above the head and with a conical rim 19 bearing against the bottom of the head, and a flange 20 is projected downwardly of the rim. The flange 20 is in the form of two frustums of cones having a 70 common small circle. The flange 20 is slotted, said slots extending radially along the rim 19 to a distance where the solid unslotted portion of the rim is of a diameter equal to the diameter of the small circle of the cones. 75

The ejector comprises a disk 21 provided with a perforated hub 22. The disk is countersunk to be flush with the head of a bolt 23 adapted to be projected through the perforated top of the 80 cylinder 18, the projecting portion of the bolt being threaded for a nut 24 adapted to suspend the ejector under the rim 19 and within the small circle of the flange 20. Inside the cylinder 18 is mounted a spring 85 coil wound on the bolt 23 between the top of the cylinder 18 and the top of the hub 22. 25 represents a cap mounted over the projecting portion of the cylinder 18.

The cap shown in Fig. 4 comprises a circular top 26, a flange 27, and an expanded corrugated rim 28.

Having thus described my machine, it is operated as follows:—

The bottle 30, is mounted on the platform 95 with its mouth centrally under the expanded mouth 17 of the holder, a cap is inserted through the opening of the holder with its rim on top of the contracted rim 16 of the holder. The lever 12 is then forced downwardly to cause the gear to move the rack 8 upwardly. The upward movement of the rack carries the bottle with its mouth against the cap and forces the cap upwardly within the lower portion of the flange of 100 the die. By exerting sufficient pressure upon the lever 12 the cap is forced through the small circle common to the flange 20, and the rim of the cap is forced by this contracted portion of the flange over the lip of the 105 bottle, at the same time the ejector holds the top of the cap flush against the mouth of 110

- the bottle. The spider legs formed by slotting the flange and a portion of the rim of the die permits these legs to articulate slightly at the junction with the rim of the die. As the cap is forced through the small circle of the flange 20, the ejector is forced upwardly against the bottom of the rim of the die, and its hub is forced within the cylinder 18 thus compressing the spring. 5
- 10 The lever is then moved in the opposite direction, thus releasing the pressure on the ejector, the spring then expands, causing the ejector to force the cap outwardly of the die. The platform can then be lowered by 15 the further downward movement of the lever until the top of the bottle is below the holder, when it is free to be removed.
- What I claim as new and desire to protect by Letters Patent, is:—
- 20 1. In a capping machine, a vertical bored head, a hollow cylinder projected through the bore of the head, said cylinder provided with a perforated top above the head and with a conical rim below the head bearing 25 against the bottom of the head, a flange extended downwardly of the rim, said flange comprising a pair of frustums of a cone

having a common small circle, said flange being divided into vertical sections by slots which terminate above the junction of the 30 flange with the rim.

2. In a bottle capping machine the combination with a bottle support and a capping head and means to move one of them relatively to the other, of a crimping die 35 socketed in said head, said die having a small and a large diameter and a dished plate connecting them, the small diameter being orificed for the reception of an ejector and slots running longitudinally the full 40 length of the large diameter and through part of the dished plate forming a resilient mouth, the large diameter being bent inwardly and then outwardly on a circle near its open end, the inner diameter of 45 said circle being smaller than the diameter of a bottle cap.

In testimony whereof I have signed this specification in the presence of two subscribing witnesses.

FRANK C. APPLEGATE.
